UNITED STATES PATENT OFFICE.

HAYDEN DAWSEY, OF MEROM, INDIANA.

PRESS.

SPECIFICATION forming part of Letters Patent No. 678,548, dated July 16, 1901.

Application filed November 13, 1900. Serial No. 36,402. (No model.)

To all whom it may concern:

Be it known that I, HAYDEN DAWSEY, a citizen of the United States, residing at Merom, in the county of Sullivan and State of Indiana, have invented a new and useful Improvement in Presses, of which the following is a specification.

My invention relates to an improvement in presses designed to press fruits, vegetables,

10 and other substances and strain the juice or other liquid therefrom, and has for its object to provide a press which is simple and inexpensive in construction and easy to manipulate.

15 It consists of the features and combination of features, as more fully hereinafter described and claimed.

Referring to the drawings, Figure 1 is a side elevation; Fig. 2, a top plan view; Fig. 20 3, a cross-section on line $x-x$ of Fig. 1.

In the drawings, in which like numerals denote like parts throughout the several views, 1 represents the body of the press, which comprises an annular ring 2, provided with a 25 downwardly depending frame 3, having a rack 4 on the upper portion of the front and a handle 5 extending from the rear thereof.

6 is a colander or strainer provided with an annular flanged rim 7, which is adapted to 30 fit over and be carried on the ring 2.

8 is a plunger with a circular head 9, which tapers from the top downward to correspond to the shape of the colander or strainer in which it operates. 10 is a bracket projecting from the upper surface of said plunger-head and provided with an eye 11.

12 is a plunger-rod having a forked lower end 13 pivoted to the bracket 10 by a pin 14 and at its upper end provided with an elongated slot 15 and a set-screw 16.

17 is a detachable hand-lever which passes through the slot 15 of the plunger-rod 12 and is provided with a hole 18 in its end. The plunger-rod is adapted to be adjusted on the 45 said lever to the desired point and then secured at such point by the set-screw 16. The purpose of adjusting the plunger-rod on the lever is to compensate for the change of position resulting from the adjustment of the 50 said lever and for keeping the plunger-head in the center of the colander.

19 is an adjustable link, the upper end of which engages the hole 18 of the hand-lever 17 and the lower end engages the teeth of

the rack 4 of the frame 3 of the press and 55 provides an adjustable pivotal connection between said lever and frame. The extent of the stroke of the plunger is regulated by adjusting the link 19 up or down on the rack 4.

60 By having the several different parts removable it adapts them to be more readily cleaned.

I do not wish to be restricted to the exact construction as herein shown and described, 65 as the same may be changed somewhat without departing from the spirit of my invention.

The operation is as follows: The link 19 is disengaged from the rack 4 and the plunger-head 9 and lever 17 are removed. The colander or strainer is then filled with the material to be pressed, the plunger-head, lever, and link again placed in position, and the lever depressed, which causes the plunger-head to be forced downward toward the bottom of the colander or strainer, thereby pressing the soft material therein and expressing the juice or other liquid through its perforations.

80 Having thus described my invention, what I claim is—

1. A press comprising a ring with a handle, a frame depending from said ring provided with a rack, a colander or strainer carried on 85 said frame, a lever having a longitudinally-adjustable plunger-rod thereon carrying a plunger, said plunger-rod adapted to be adjusted and fixed at different points on said lever, and means for connecting said lever with said rack, substantially as shown and described.

2. A press comprising a depending frame with a ring at the top, a handle at the rear, and a rack at the front thereof, a colander or 95 strainer carried by said ring, a detachable lever carrying a link which engages said rack, and a plunger having a plunger-rod provided with a slot through which said detachable lever is adapted to pass, and means for 100 securing said plunger-rod to said lever, substantially as shown and described.

In testimony whereof I hereto affix my signature in the presence of two witnesses.

HAYDEN DAWSEY.
